O. MILLER.

CAR AXLE LUBRICATOR.

APPLICATION FILED DEC. 30, 1916.

1,230,821.

Patented June 19, 1917.

FIG. 4.

INVENTOR:
Otto Miller.

BY his ATTORNEY:

A. M. Carlsen.

UNITED STATES PATENT OFFICE.

OTTO MILLER, OF DALTON, MINNESOTA.

CAR-AXLE LUBRICATOR.

1,230,821.

Specification of Letters Patent. Patented June 19, 1917.

Application filed December 30, 1916. Serial No. 139,955.

To all whom it may concern:

Be it known that I, OTTO MILLER, a citizen of the United States, residing at Dalton, in the county of Ottertail and State of Minnesota, have invented a new and useful Car-Axle Lubricator, of which the following is a specification.

My invention relates to lubricating devices for car axles; and the object is to provide an efficient lubricating device by which to gradually feed lubricating oil to the journaled ends of the axles of railway cars.

In the accompanying drawing, Figure 1 is a substantially central vertical longitudinal section of the journaled end of a car axle and its journal box with my improved lubricator applied thereto and shown partly in section and secured in the usual lid 8 which is not in section. Fig. 2 is a bottom view of the main body 11 of the lubricator. Fig. 3 is a detail side view of the central rod 23 in Fig. 1. Fig. 4 is a top view of the oil cup or reservoir of the device. Fig. 5 is a right hand end view of the cap 14 in Fig. 1. Fig. 6 is an end view of the collar 29 in Fig. 1.

Referring to the drawing by reference numerals, 1 designates the regular journal box of a car axle 2 in whose ends there are always central funnel shaped cavities 3 namely those provided for the centers of the lathe in which the axle was turned. 4 are the usual side-braces secured by vertical bolts 5 to the top and bottom of the journal box. 6 designates the usual pocket at the outer end of the journal box for holding cotton waste or similar absorbent material 7, saturated with lubricating oil which is gradually taken up by the journal 2 when it rotates. Said pocket is closed by an inclined lid 8 suspended from a hinging pintle 9 and having at its lower end a lug 10 for taking hold of in opening the lid.

In some instances the lid 8 may stand in vertical position and in some cases it is also slideable. In either case I secure the threaded tube 11 of my lubricating device in a hole I make in said lid, applying a jam-nut 12 at each side of the lid. If the lid is of the inclined type shown in Fig. 1, I make the nuts fit the lid indirectly by giving each nut an inclined or V-shaped washer 13. The rear end of the tube 11 is closed by a threaded cap 14, the removal of which admits of inserting a cleaning rod to clean the tube. The cap is given a T-handle 15, which en-

ables one to screw it tight without tools and also to pull on the lid 8 if it sticks in old grease or in snow, or otherwise.

Near the inner end the underside of the tube is provided with an oil outlet 16, which may be reduced to any desired size by covering more or less of it by a movable collar 17, which is held in place by a set-screw 18. Near the outer end of the tube is provided an oil cup 19 having a screw cover 20 with a flat stem 21, through which there is an aperture 22, so that the cover may be unscrewed and screwed tight either by a monkey wrench placed on the stem or a spike put into the hole 22.

Slidably fitted within the tube 11 is a cylindrical rod 23, having its main portion provided with spiral grooves 24, and its inner portion formed with a slot 25, and its inner end with a cone 26 having longitudinal corrugations 27, which engage the inner sides of the central cavity 3 in the axle and thus causes the rod to rotate with the axle. To insure engagement the cone is under pressure of a spring 28, whose outer end is resisted by a collar 29 having a diametrical pin 30 extending through the slot 25 in which it slides with the collar, so that when the rod is rotated by the axle, the collar is resisted by and wears against the front end of the tube 11. The degree of compression of the spring is thus automatically regulated by the distance, which may vary some, between the end of the axle and the lid 8, after the tube 11 has been secured in the lid as correctly as practical to suit said distance.

The oil cup may be cast integral with the tube 11 or it may be threaded as at 19^a into a nipple 11^a on the tube. And in applying the device to new lids 8, the lid may have the washers 13 cast integral with the lid.

In operation, when the cup 19 is filled with oil and the axle 2 rotates as the car is moving, the axle rotates the rod 23, whereby the oil is prevented from clogging in the tube 11 through which it is moved partly by its gravity and partly by the spiral grooves 24, and drips as at 31 upon the material 7, from which the axle draws it by contact and rotation, or it may flow therefrom into an oil groove 32 in the bearing underneath the axle; all of which may be so much varied that no exact form has been illustrated.

What I claim is:—

1. The combination with the lid of a car axle box of a tube secured in said lid in

- axial alinement with the axle, a rod rotatable in the tube and having its inner end spring-pressed into the center of the axle and its body provided with grooves, and an oil cup mounted upon the outer end of the tube to feed oil through the same, said tube having beyond the inner side of the lid in its lower side an oil passage and means for regulating the size of said passage.
- 10 2. The combination with the lid of a car axle box, of a tube secured in said lid in axial alinement with the axle, a rod rotatable in the tube and having its inner end spring-pressed into the center of the axle and its body provided with grooves, and an oil cup mounted upon the outer end of the tube to feed oil through the same, said tube having beyond the inner side of the lid in its lower side an oil passage and means for regulating the size of said passage, and means for adjusting said tube in said lid according to the distance between the lid and the end of the axle.
- 15 3. The combination with the lid of a car axle box, of a tube secured in said lid in axial alinement with the axle, a rod rotatable in the tube and having its inner end spring-pressed into the center of the axle and its body provided with grooves, and an oil cup mounted upon the outer end of the tube to feed oil through the same, said tube having beyond the inner side of the lid in its lower side an oil passage and means for regulating the size of said passage, said 20 grooves on the rod extending spirally about the same.
- 25 4. The combination with the lid of a car axle box, of an oil cup mounted upon the

outer side of the lid, a tube extending therefrom through the lid and having a controlled lateral outlet for oil within the box, a grooved rod slideable and rotatable within the tube in axial line with the car axle, said rod having its inner end formed with a longitudinally grooved cone adapted to enter the center of the axle, and near said cone a longitudinal slot, a collar loosely fitted on the rod and having a pin extending diametrically through the slot, a compression coil spring upon the rod between the cone and the collar, pressing the latter at all times against the inner end of the tube and thus holding the cone yieldingly in contact with the axle.

5. The combination with the lid of a car axle box, of an oil cup mounted upon the outer side of the lid, a tube extending therefrom through the lid and having a controlled lateral outlet for oil within the box, a grooved rod slideable and rotatable within the tube in axial alinement with the car axle, said rod having its inner end formed with a longitudinally grooved cone adapted to enter the center of the axle, and near said cone a longitudinal slot, a collar loosely fitted on the rod and having a pin extending diametrically through the slot, a compression coil spring upon the rod between the cone and the collar, pressing the latter at all times against the inner end of the tube and thus holding the cone yieldingly in contact with the axle, said tube having its outer end normally open, and a removable cap closing said open end of the tube.

In testimony whereof I affix my signature. 75
OTTO MILLER.
